Atty.

UNITED STATES PATENT OFFICE

2,241,562

EXTENSION FITTING AND CAP THEREFOR

Louis B. Wackman, St. Louis, Mo., assignor to
 American Flange & Manufacturing Co., Inc.,
 Chicago, Ill., a corporation of Illinois

Application January 2, 1932, Serial No. 584,316
 Renewed March 16, 1938

4 Claims. (Cl. 220—39)

This invention relates to certain new and useful improvements in an extension fitting and a cooperable cap therefor, the fitting being built in the head wall of a container so as to form an extended bushing or bung for the container with which both the closure plug and the cap are cooperable, these being the primary objects of the invention.

Another object of the invention is to provide the head wall or barrel head of a container with an extending ring or neck which is threaded interiorly and is outwardly curled or turned at its upper or extending end for providing an anchorage for an underclinched sealing cap.

Still another object of the invention is to provide a bushing of an improved construction for wholly receiving the closure plug and with means whereby a sealing cap can be secured to the bushing for concealing both the bushing and the plug.

A still further object of the invention is to provide an improved fitting in the form of a bushing for a metallic container for permitting a cooperable sealing cap to be clinched thereto in a covering or concealing condition and the cap being provided with means whereby the same can be easily and quickly removed and can be destroyed in its removal.

Other and further objects will appear in the specification and be specifically pointed out in the appended claims, reference being had to the accompanying drawing, exemplifying the invention, and in which:

Figures 1, 2 and 3 are vertical sectional views illustrative of forming the bushing or fitting before it is engaged in the barrel head.

Figure 4 is a vertical sectional view through the bushing and a fragmentary portion of the barrel head showing the manner of mounting the bushing in the head before it is secured to the head.

Figure 5 is a vertical section taken through a portion of the barrel head and the bushing when the bushing is in a closed and sealed condition.

Figure 6 is a plan view of Fig. 5.

With reference to the accompanying drawing and particularly to Figs. 1, 2 and 3, in the manufacture of this improved fitting, sections are cut from a metallic tubular length, each cut section then being in the form of a ring 1, said ring after being severed then being counterbored at one end as designated at 2 for providing an annular tapering seat as shown at 3 in Fig. 1.

Obviously the counterbore 2 in the ring 1 provides a relatively thin annular wall 4, this wall

in the next operation on the ring 1 being outwardly turned and curled thereby providing an annular lip or bead 5 as shown in Fig. 2.

After the ring is made in the form shown in Fig. 2, it is then provided with an inner beveled face 6 on the end opposite to the curled end of the ring. The ring is then interiorly threaded as designated at 7 from the seat 3 to the beveled face 6 (Fig. 3). The ring is then ready for mounting in the barrel head.

In mounting the ring in the barrel head, attention is directed to Fig. 4 in which it will be seen that the barrel head 8 is provided with an annular raised portion 9 having a depending annular flange 10 which is formed around the ring or bung opening of the barrel head. The bung opening is of a size so that the ring 1 can be snugly positioned therein in the manner shown in Fig. 4 and in this position, the beveled end of 10 the ring is ready for securing by welding to the wall of the flange 10 of the raised portion 9, the welding joint between the beveled end of the ring and the wall of the flange 10 of the barrel head being shown at 11 in Fig. 5.

25 The formation of the annular raised portion 9 and the flange 10 therearound obviously provides an annular reinforcement around the bung hole and the snug fitting of the ring 1 in the bung hole and the securing of said ring by welding to the flange as shown in Fig. 5, obviously provides an extremely rigid and strong fitting structure which will withstand the repeated securing and unfastening of the closure plug 12 in the ring 1.

35 The closure plug 12 at its upper or outer end is provided with an annular groove 13 for the reception of a gasket 14, the gasket being retained by the plug and when the plug is threadingly engaged in the thread 7 of the ring 1, the gasket 14 will be firmly seated in a packing 40 manner on the seat 3 of the ring 1, the plug being threadingly operated in the ring 1 by wrenching means engaged in the polygonal socket 15. The flange or head 16 of the plug 12 being of the approximate diameter of the threads of the plug 45 permits the flange to be seated well within the counterbored part of the ring 1.

After the plug 12 has been properly secured in the ring 1 in a seal tight manner, a sealing cap 17 having an extending annular skirt wall 18 50 and a gasket 19 is then engaged over the lip 5 of the ring 1 and the inner end of the wall 18 is then clinched beneath or inwardly of the bead 5 in the manner shown in Fig. 5, the sealing of the cap 17 over the ring 1 not only covering both 55 the top of the ring and the plug 12 for prevent-

ing unauthorized access but also forming an outer seal to the ring for preventing leakage from the container in the event that the plug 12 became loosened as the cap 17 is clinched over the bead 5 of the ring 1 by an operating tool which will firmly seat the gasket 19 of the cap on top of the bead 5 of the ring.

After shipment of a container having this improved fitting thereon and the sealing cap 17 and it is desired to remove the cap for removal of the closure plug 12, one of the projections 20 of the cap of which there are a pair as shown extending from the annular wall 18 of the cap, is gripped and outwardly pulled and as the cap is provided with a pair of spaced weakened or scored lines 21, from between which the projections 20 extend, the outward pulling on a projection will sever or partially sever the cap on the weakened lines 21. The severing of the cap in this manner will not only provide for easy removal of the severed halves of the cap but in addition will destroy the cap against re-use.

Obviously constructional modifications of the device are possible without departing from the spirit of the present invention and therefore it is to be understood that it is not necessary to limit the invention by the terms used in the foregoing description, excepting such as the state of the art may require.

What I claim is:

1. In a structure of the class described, an extending metallic tubular bushing providing an opening in a wall of the container, the lower or inner part of which opening is threaded and the outer part of which opening is provided with an annular bead and an unthreaded seat tapering downwardly and inwardly from the outer edge of said opening to the top of its threaded part, a plug having a threaded body with the outer end of the plug of the approximate diameter of the threads, a gasket carried by said plug between its outer end and the threads thereof and having a diameter larger than the plug and adapted to be deformed against said seat, and leak-proof and tamper-proof sealing means including a cap having its cylindrical skirt contracted around said bead, and a gasket confined and deformed between said bead and the top of the cap and the cap skirt.

2. In a structure of the class described, an extending metallic tubular bushing providing

an opening in a wall of the container, the lower or inner part of which opening is threaded and the outer part of which opening is provided with an unthreaded seat tapering downwardly and inwardly from the outer edge of said opening to the top of its threaded part, a closure plug having a threaded body part adapted to engage said threaded opening and having a head of the approximate diameter of the threads thereof, and a readily deformable gasket carried by said plug between its head and threaded body part and adapted to be deformed against said seat between said seat and plug head and above the threads of said opening.

3. In combination, a container wall having an opening therein and a bushing member received in said opening, the stock of said container wall surrounding said opening being bent out of the plane of said wall and being provided with a return bend forming an inwardly directed flange defining said opening, said flange and said bushing member being unitarily joined by welding at the free ends thereof and portions of said bushing member and said flange lying side by side throughout the height of said flange, thereby tending to support one another, said flange and said bushing member extending outwardly from substantially the plane of said container wall, whereby the bushing member is secured to a container wall in welded reinforced relation with respect thereto without having projecting parts of the connection extending within the container to interfere with full drainage of the contents thereof.

4. In combination, a container wall having an opening therein and a bushing member received in said opening, the stock of said container wall surrounding said opening being bent out of the plane of said wall and being provided with a return bend forming a flange defining said opening, said flange and said bushing member being integrally joined at the inner free ends thereof and portions of said bushing member and said flange extending from said joint lying in opposed relation, whereby a shock imparted to the outer end of the bushing tending to drive the same into the container will be resisted by the bushing and flange locking against each other to protect the joint, said bushing member being internally threaded and having a gasket seat formed around its upper end.

LOUIS B. WACKMAN.
